UNITED STATES PATENT OFFICE.

JOHN POPPER, OF MONTREAL, QUEBEC, CANADA.

DESIGN FOR A PERFUME BOTTLE OR SIMILAR CONTAINER.

Application filed January 21, 1928. Serial No. 24,977. Term of patent 7 years.

To all whom it may concern:

Be it known that I, JOHN POPPER, a subject of the King of Great Britain, and resident of the city of Montreal, in the Province of Quebec and Dominion of Canada, have invented a new, original, and ornamental Design for a Perfume Bottle or Similar Container, of which the following is a specification, reference being had to the accompanying drawing, forming part thereof.

The figure is a perspective view of a perfume bottle or similar container, showing my new design.

I claim:

The ornamental design for a perfume bottle or similar container, as shown.

In witness whereof, I have hereunto set my hand.

JOHN POPPER.
